BUFFING WHEEL

Wayne S. Thomas, Detroit, Mich.

Application July 20, 1937, Serial No. 154,651

3 Claims. (Cl. 51—193)

My invention relates to a buffing wheel and one of the objects of the invention is to provide means for ventilating the wheel that it may not become excessively heated thereby causing the fabric to scorch or burn due to the high speed at which it rotates.

A further object is to provide a buffing wheel, relatively inexpensive in construction, which may be of any required width, the buffing-fabric being spirally wound upon a helically coiled wire,—the respective convolutions of the fabric being spaced apart near the core for the circulation of air,—the fabric at the perimeter of the wheel presenting a uniformly compact, dense surface for contact with the surface to be buffed.

A further object of the invention is to provide means whereby the convolutions of the wire on which the buffing fabric is mounted, are securely held against deformation between end plates mounted on the driving spindle, the respective convolutions of wire being formed with whorls or volutes spaced apart circumferentially, but in axial alignment with like whorls formed respectively in each adjacent convolution of wire, to receive a plurality of rods coaxially disposed in relation to the driving spindle of the buffing wheel, the ends of the respective rods being supported and held against dislodgement by end plates mounted on the spindle at each side of the buffing wheel.

Other objects of the invention and improvements in construction will be hereafter described and shown in the drawings.

In the drawings accompanying the specifications:

Figure 1 is a sectional elevation of the buffing wheel, taken on or about line 1—1, of Figure 4.

Figure 2 is a diagrammatic elevation of the helically coiled wire and respective end plates,—connected together through the coiled wire by a plurality of coaxially disposed rods, fitted with adjustable nuts.

Figure 3 is a detail cross-sectional view through the buffing fabric, as looped around the wire-coil, taken on or about line 3—3, of Figure 1.

Figure 3a, is a similar view, showing one of the openings in the buffing fabric to receive one of the whorls of the coiled wire, also a fragment of one of the coaxial rods extending through the 50 whorl.

Figure 4 is a cross-sectional view through the buffing wheel, taken on or about line 4—4, of Figure 1.

Figure 5 is a fragmentary sectional elevation 55 of the fabric and supporting wire-coil on which

it is mounted, taken on or about line 5—5, of Figure 3a, showing the pleated fabric forming the buffing wheel.

Figure 6 is a diagrammatic perspective view of the wire-coil and the respectively aligned whorls 5 of each convolution of wire, the buffing-fabric being supported on the wire;—and through the whorls of the wire-coil extend coaxially aligned rods, shown in broken lines, a fragment of the buffing-fabric being shown secured to the wire 10 coil.

Figure 7 is a modification of the wire-coil, showing a linking member secured to the coil, adapted to receive the coaxially aligned rods supported by the end plates.

Referring now to the reference characters on the drawings:

Numerals 1, denotes the driving spindle, 2—2 indicate end plates mounted on the spindle, between which is a continuous strip 3, comprising 20 a plurality of pleated layers of fabric, looped in U-shaped form in cross-section,—upon a helically coiled supporting wire 4, encircling the driving spindle between the end plates 2—2, mounted thereon.

The respective convolutions of the wire coil 4, are provided with a plurality of inwardly projecting whorls 5, aligned with like whorls on each adjacent convolution of the wire, to receive a plurality of coaxially disposed rods 6, extending 30 through the aligned whorls of the respective convolutions of the helically coiled wire 4. The rods 6, are supported at their ends in the end plates 2—2. The rods 6, are fitted with adjusting nuts 7, that the end plates may be drawn toward each other to grip the helically coiled fabric adjacent to the core of the buffing wheel. The end plates 2—2 are preferably provided with a hub portion 2a, the abutting ends of the hub being respectively formed with a notch 2b, and an interlocking tongue 2c, shown in dotted lines in Figure 4.

It will be obvious that air will freely circulate through the openings 3a, in the buffing-fabric,—see Figure 4,—provided for the passage of the inwardly extending whorls of the helical coil or 45 supporting wire, and also through the pleated layers of fabric as clearly disclosed in Figure 5, and Figure 3a,—a circulation of air is thus provided materially adding to the longevity or life of the buffing wheel.

It has been proven by numerous tests that the buffing-fabric of the present invention remains cool and unscorched, while other buffing wheels mounted on the same shaft and running at the same speed and under like conditions, in contact 50

with like work, become heated to such an extent that the fabric was soon scorched and lost its stamina and vitality.

In the modification shown in Figure 7, a linking member 8, is secured to the coil, to receive the coaxially aligned rods 6, supported by the end plates.

What I claim is:—

1. A buffering wheel comprising a spindle; means on said spindle to receive and support an annular buffering wheel; a helically coiled wire, having a plurality of means, spaced apart, and respectively adapted to register with other of said means to receive a plurality of rods axially aligned with the spindle; a plurality of rods extending through the said rod-receiving means of the helically coiled wire; and a continuous helically-wound buffering fabric, supported by said helically coiled wire.
2. A ventilated buffering wheel comprising a spindle; means on said spindle spaced apart to receive and support an annular buffering wheel; a helically coiled wire, having a plurality of relatively small whorls, spaced apart and respectively adapted to register with other of said whorls to receive a plurality of rods axially aligned with the supporting spindle; a plurality of rods extending through the respective registering whorls of the helically coiled wire; and a continuous helically wound buffering-fabric supported by said helically coiled wire, having convolutions spaced for the passage of air, whereby air for cooling and ventilating said buffering-fabric may pass between the convolutions of the buffering-fabric.
3. A ventilated buffering wheel comprising a spindle; means mounted on said spindle to receive and support an annular buffering-wheel; a helically coiled member having a plurality of relatively small apertures spaced apart, and respectively adapted to register with other of said apertures; a plurality of rods extending through the aligned apertures of the helically coiled member; and a helically wound buffering-fabric, supported by said helically coiled member, having convolutions spaced for the passage of air, whereby air for cooling and ventilating said buffering-fabric may pass between the convolutions of the buffering-fabric.
4. A ventilated buffering-wheel comprising a

spindle; plates spaced apart on said spindle to receive and support an annular buffering-wheel; a helically coiled wire, having a plurality of means respectively adapted to register with other like means to receive a plurality of rods aligned with the supporting spindle; a plurality of rods extending through the said respective registering rod-receiving means of the helically coiled wire; and a continuous helically wound buffering-fabric supported by said helically coiled wire, whereby air for cooling and ventilating said buffering-fabric may pass between the convolutions of the buffering-fabric.

5. A ventilated buffering wheel comprising a spindle; plates spaced apart on said spindle to receive an annular buffering wheel; a helically coiled member having a plurality of means spaced apart and respectively adapted to register with other like means to receive a plurality of rods; a plurality of rods extending through the respective registering rod receiving means of the helically coiled member; and a continuous helically wound buffering fabric supported by said helically coiled member, whereby air for cooling and ventilating the buffering fabric may pass between the convolutions of said buffering fabric.

6. A buffering wheel consisting of a helically wound fabric; a helically wound member over which the buffering fabric is folded at its inner periphery; a plurality of supporting means for interlocking the convolutions of the helically wound member; and means securing said supporting means to a spindle.

7. A buffering wheel consisting of an undivided helically wound buffering fabric; a helically wound member to which the undivided convolutions of the helically wound buffering fabric are secured; a plurality of supports for interlocking the convolutions of the helically wound member; and means for securing said supports to a spindle.

8. A buffering wheel comprising a helically wound fabric; a helically wound member adapted to support and space the convolutions of the helically wound fabric; and a plurality of aligned supporting elements engaging the convolutions of the helically wound member, whereby it is secured against deformation; and means for coupling the supporting elements to a spindle.

WAYNE S. THOMAS.
